UNITED STATES PATENT OFFICE.

MACK S. RICHESON, OF ORCHARD, COLORADO.

LOCKING MECHANISM FOR THE DUMPING-PLATFORMS OF SUGAR-BEET-LOADING STRUCTURES.

1,195,398.

Specification of Letters Patent. Patented Aug. 22, 1916.

Application filed December 27, 1915. Serial No. 68,857.

To all whom it may concern:

Be it known that I, MACK S. RICHESON, a citizen of the United States of America, residing at Orchard, county of Morgan, and 5 State of Colorado, have invented a new and useful Locking Mechanism for the Dumping-Platforms of Sugar-Beet-Loading Structures, of which the following is a specification.

10 My invention relates to a new locking mechanism for the tilting wagon dumping platforms of railway car beet sugar loading structures; and the object of my invention is to provide a safe and reliable manually operating platform locking mechanism that will lock the tilting platform automatically and that will hold the platform securely and safely, and that can be unlocked and will release the tilting platform by foot 15 pressure. I attain these objects by the mechanism illustrated in the accompanying drawings, in which:

Figure 1, is a transverse sectional view through the structure and the rocking platform showing the said platform locked in a horizontal position by the improved locking mechanism. Fig. 2, is a transverse, sectional view showing the platform tilted as when a wagon is being dumped therefrom, 20 the parts of the locking mechanism being in the position they assume when the platform is thus tilted.

Similar letters of reference refer to similar parts throughout the several views.

25 Referring to the drawings, in Figs. 1 and 2, is illustrated a portion of a dumping structure, such as is used in the beet sugar raising districts of Colorado. This structure is built of wood and comprises suitable 30 inclined approaches not shown, which terminate at their top ends in a tilting platform 3, upon which the wagon loads of beets are driven. This platform is then tilted side- 35 wise with the wagon load of beets on it, and the lower side boards of the wagon are 40 swung out and the beets slide out of the wagon onto a row of slats 4, down which the beets slide into a freight car.

45 The tilting platform when a load of beets 50 is on it, is arranged so that it will tilt up quickly. Consequently the platform exerts a constant upward tilting pressure on its upward moving side, and the essential object of my invention is to provide a locking mechanism that will securely lock the plat-

form against accidental tilting movement, but which can be quickly and easily released. To this end I provide the tilting platform 3 with a base plate shoe 5, which as illustrated 60 is of the rocking cradle type. The platform is made of heavy planking 6 that is supported on cross sills 7. This platform rolls on curved runners 8 that rest on cross beams 9. The shoe 5 is securely bolted to the up-

wardly moving edge of the tilting platform, 65 and to it I pivotally secure the lower end of an upright jointed or toggle jointed bar 10, which I term the locking bar. This locking bar is made in two portions 10 and 11, the upper end portion of which is pivotally 70 connected to an abutment shoe plate 12, that is secured to a cross beam 13, that is strongly secured to two vertical posts 14. The pivotal joint 15 of the locking bar is preferably positioned at a little more than half way 75 from the base plate or tilting platform shoe of the whole length of this toggle bar. The pivotally connecting knuckle of the two parts or portions of this bar forms a knuckle 80 joint or a knuckling connection in the bar, and it preferably consists of the meeting 85 ends of the two parts of the bar, being pivotally and overlappingly connected together by a pivotal bolt 16, so that the lower part engages the upper part and limits its locking movement. The overlapping connection of the jointed ends of this toggle bar is preferably formed by a yoke-shaped extending 90 end portion 17 that is formed on the upper end of the lower end portion 10 of this toggle bar. This yoke shaped extension portion is made to straddle and partially enclose the edge and the opposite sides of the adjacent end of the upper portion of the jointed bar. Above the joint 15 a cross 95 lever 18 is securely bolted at one end, which end laps around the edge of the bar 11 to prevent the lever from turning on its bolt. The outer end of this lever is provided with 100 an apertured eye 19 and it fits loosely over an adjustable threaded eye bolt 20 that extends loosely through it. The upper end of this eye bolt is provided with a handled nut 21 which threads loosely on the threaded eye bolt. A check nut 22 is threaded on the end of the eye bolt. The lower end of the eye bolt is provided with a hook, on which one end of a tension spring 23 is placed. The opposite end of this spring is connected 105 to the hook end of an eye bolt 24, that is se- 110

surely bolted to the flat end of a lever 25, the opposite end of which is bolted to the lower portion of the jointed bar 10; the adjacent end of this lever engages adjacent edge of the bar to prevent the lever from turning on its bolt.

In Fig. 1, my improved locking mechanism is illustrated in a locked position, in which position the center of the pivotal bolt 16 is on the opposite side of a center line from the contraction tension spring 23, which exerts a strong enough pull on the opposite end portions of the jointed bar to hold that bar securely locked in that out of center alignment position. In this position the bar is slightly knuckled and the yoke end of the lower portion of this bar bears tightly against the adjacent edge of the upper portion of the bar, which prevents the bar from moving any farther away from its holding spring. Consequently in the position my improved tilting platform locking mechanism is shown in Fig. 1, the tilting platform 3 is locked in a substantially horizontal plane and in a loaded wagon receiving position.

As soon as a loaded wagon has driven on the platform into position to dump the load of beets, the operator breaks the lock of the vertical locking bar by breaking the off-centered joint, which he does by moving the pivotally jointed ends of the bar beyond a straight line connecting the opposite ends of the said bar. There are a number of ways that this feature of my invention can be effected. I preferably however arrange to break this locking bar's joint in the following manner: To the posts 14 I pivotally secure in boxes A, the opposite end portions 27 of a crank rod, the central swinging portion 28 of which is normally held against the outer edge of the locking bar by the weight of a foot tripping rod portion 29 that depends from one of the ends of the crank rod, and when the operator desires to break the locking joint of the locking bar, he puts a foot against the end of the foot tripping portion of this crank rod and moves it to cause the swinging center rod of the crank rod to press against the locking lever and throw its jointed ends across the center of this rod, which unlocks this joint and instantly afterward the platform tilts and its side to which the locking mechanism is attached tilts upwardly in the direction of the arrow, the platform with its load being slightly over-weighted so as to tilt in that direction.

The tilting movement of the platform tilts the wagon, which is held from sliding off of it by the wheel rail 30 and the hub rail 31. When the platform is tilted up to the full limit of its upward movement, the locking mechanism is moved into the position shown in Fig. 3, which stretches the spring

23 as shown. After the load has been dumped the spring helps to draw the parts of the locking bolt back into their locked position, as the platform moves down. The spring, however, may be dispensed with if desired, as the platform is arranged to roll tiltingly back into its flat horizontal position, and as it moves into that position the locking bar will again automatically lock itself by throwing its pivotal end portions past its center line between its end pivotal connections between the shoes 5 and 12. The center of gravity of the loaded wagon when on the platform, is outside the line of the center of gravity of the platform, as shown by the dotted position of the wagon in Fig. 1, and therefore, when the joint in the locking bar is broken, the platform rocks by gravity. Pressure applied to the high end of the tilted platform in connection with the pull exerted by the spring 23, will restore the platform to a horizontal position.

My invention provides a very strong, reliable automatic lock for the tilting dumping platforms of beet dumps, and while I have illustrated and described the preferred construction and arrangement of my invention, I do not wish to be limited to it, as many changes might be made without departing from my invention.

Having described my invention, what I claim as new and desire to secure by Letters Patent, is:

1. The combination with a supporting structure, and a rocker supported platform mounted thereon, of a toggle latch, the ends of which are pivotally connected respectively to one side portion of said platform and to said supporting structure, arms extending at right angles from the members of said toggle latch, a contraction spring connected at its ends to said arms, and means mounted on the supporting structure for breaking the joint in said toggle latch, thereby to permit tilting of the platform.

2. The combination with a supporting structure and a rocker platform supported thereon, of a vertically disposed toggle latch hinged at one end to one side of the platform, and at its other end to said supporting structure, a stop on one member of said toggle latch which engages the other member thereof to hold said latch in a locked position, an arm extending at right angles from each member of the toggle latch, a contraction spring connecting said arms, and a lever hinged to said supporting structure for breaking the joint in said toggle latch thereby to permit tilting of the platform.

3. The combination with a supporting structure and a rocker platform mounted thereon, of a toggle latch connecting one side of said platform and said supporting structure, one member of said latch having

a channel form of stop which extends beyond the joint of said latch and engages the other member thereof to hold the latch in locked position, arms extending at right angles from said latch members in the direction of their unlocking movement, a tension device on one of said arms, a contraction spring connected at one end to said tension device and at its other end to the opposite

arm; and a lever mounted on the supporting structure for breaking the joint in said latch thereby to permit tilting of the platform.

In testimony whereof I affix my signature in presence of two witnesses.

MACK S. RICHESON.
